UNITED STATES PATENT OFFICE.

GUSTAF E. NILSON, OF NEW YORK, N. Y.

WRENCH.

1,306,020.

Specification of Letters Patent. Patented June 10, 1919.

Application filed February 24, 1919. Serial No. 278,754.

To all whom it may concern:

Be it known that I, GUSTAF E. NILSON, a citizen of Finland, residing at New York city, county and State of New York, have invented certain new and useful Improvements in Wrenches, of which the following is a full, clear, and exact description.

This invention relates to improvements in wrenches, the object being, mainly, to provide a wrench, of the monkey or movable jaw variety, that can be manipulated to adjust the jaws to various sizes of nuts by one hand, that is to say, adjusted by the hand which holds the wrench. The usual form of movable jaw wrench requires the use of both hands when the jaws are to be adjusted. The jaws of my improved wrench can be adjusted and held by the same hand. The manner of carrying out the above mentioned feature, as well as other features of improvement, will be set forth in the following specification, reference being had to the accompanying drawing, wherein:—

Fig. 1 is a side elevation of an embodiment of my invention;

Fig. 2 is an enlarged edge view, looking from the left in Fig. 1;

Fig. 3 is an enlarged sectional view, the section being taken on a line 3—3 in Fig. 2;

Fig. 4 is an end view of the handle portion of the wrench;

Fig. 5 is an enlarged detail side view of the nut to operate the movable jaw adjusting spindle; and

Fig. 6 is an end view of the head of the wrench.

My improved wrench comprises a handle 7 having a head 8 consisting of a fixed jaw-member 9 and a movable or adjustable jaw-member 10 carried by a bar 11 having rack teeth 12. The bar 11 carries (in this instance) two guides 13 slidably engaging grooves or rabbets 14 in the body portion 15 of the head 8, which is slotted to form a channel 16 to receive bar 11 which carries the jaws 10. The teeth 12 of the bar 11 mesh with a worm 16 rotatably supported within the channel 16 by blocks 17 and 18. The block 17 engages a projection 19 on the worm 16 and the block 18 a projection 20. The projection or spindle 20 is pivotally connected to a block 21 which in turn is engaged by the jaw 22 of a threaded spindle 23 rotatably mounted in a channel 24 formed

in the handle 3. The outer end of the handle 55 carries a block 25 to rotatably support the adjacent end of the spindle 23.

The function of the worm 16 is to adjust jaw-member 10, or move it toward or away from jaw-member 9. The function of the 60 spindle 23, which carries a thread in the form of a helical groove 26, is to rotate the worm 16 to which it is connected. The connection between the adjacent ends of the spindle 23 and worm 16 is universal, in order that the worm can be rotated by means 65 of the angularly disposed spindle 23.

To rotate the spindle 23, I provide a slide- 70 able nut 27 carrying a web 28 to engage the helical groove in spindle 23. As can be seen in Fig. 4, the nut 27 carries guide members 29 and 30 through which spindle 23 passes, the web 28 being located between said guide members. The guide members 29 and 30 engage the channel 24 in the handle 7, the 75 channel 24 and guide members 29 and 30 being in this instance cylindrical in cross section or at least approximately so. The nut or block 27, is, during its movement longitudinally of the handle 7, guided by the 80 channel 24. During the longitudinal movement of the nut or block 27, the spindle 23 will be rotated, by the intermeshing web 28, and will in turn rotate worm 16, which rotation will cause the bar 11, and jaw 10 to 85 move toward or away from jaw 9.

The block or nut 27 can be operated, or moved longitudinally of the handle 7, by the thumb of the hand which supports or holds the wrench, or the wrench can be held 90 in such manner as to permit it to slip, by gravity, through the hand, when held in a vertical position, as indicated in Fig. 1. In any event, it is but necessary to move the block or nut 27 longitudinally of the handle 95 7 to cause spindle 23 to rotate, whereby jaw 10 will be moved toward or away from jaw 9. Both the blocks 17 and 25 are held in place by pins or screws, indicated by 31 and 32. By removing the pins or screws, the 100 blocks can be removed and the spindle 23 and worm 16 taken out; the movable jaw 10 and its bar 11 can also be taken out. Block 18 is a permanent element.

I do not limit myself to the precise construction herein illustrated, as same may be changed in various details and still be within the scope of my invention.

Having described my invention, what I claim is:

1. In a wrench, a handle, a head carried thereby and disposed at an angle relative thereto, a fixed jaw carried by the head, said handle and said jaw being provided with a communicating channel, a movable jaw carried by the head, a rack carried by the movable jaw extending into the channel in said head, a worm in said channel engaging said rack, a threaded spindle within the channel in said handle, a universal joint connecting the threaded spindle and said worm, a nut engaging said threaded spindle, and a guide-member carried by the nut slidably engaging the channel in said handle. 20
10. Signed at New York city, N. Y., this 21 day of February, 1919.
15. 2. In a wrench, a handle, a head carried thereby and disposed at an angle relative thereto, a fixed jaw carried by the head, said handle and said jaw being provided with a communicating channel, a movable jaw carried by the head, a rack carried by the movable jaw extending into the channel in said head, a worm in said channel engaging said rack, a threaded spindle within the channel in said handle, a universal joint connecting the threaded spindle and said worm, a nut engaging said threaded spindle, and a guide-member carried by the nut slidably engaging the channel in said handle. 25

GUSTAF E. NILSON.
